UNITED STATES PATENT OFFICE.

NATHANIEL BRAHAM, OF ASBURY PARK, NEW JERSEY.

PICTURE-EXHIBITOR.

1,173,923.

Specification of Letters Patent. Patented Feb. 29, 1916.

Application filed May 17, 1915. Serial No. 23,600.

To all whom it may concern:

Be it known that I, NATHANIEL BRAHAM, a subject of the King of England, residing at Asbury Park, in the county of Monmouth and State of New Jersey, have invented new and useful Improvements in Picture-Exhibitors, of which the following is a specification.

This invention relates essentially to that 10 class of picture exhibiting machines in which the advertisements or pictures are printed or otherwise produced on a pair of webs or belts adapted to travel along a sight opening located in the front of a case. 15 Each web has one end secured to the case and the other end secured to a reel, so that when the reels are actuated one of the webs while traveling along behind the sight opening will wind on a reel while the other web 20 will unwind.

One object of the invention is that while one of the webs is moving into view the other disappears while it is passing the sight opening.

25 Another object of the invention is that while the webs are being operated, a device is employed whereby a spectator is unable to see the method of winding or unwinding the webs; so as to give the effect of a vanishing picture or advertisement.

Another object of the invention is to provide a picture exhibitor with a pair of webs which are adapted to be interchanged or substituted by other webs, so that the advertisement or picture may be varied.

I construct my device so that the wear upon the webs is reduced to a minimum and stretching of the same is avoided.

The novel features of the invention are 40 more fully described in the following specification and claims and illustrated in the accompanying drawings in which:

Figure 1 represents a front elevation of a picture exhibitor embodying this invention. Fig. 2 is a vertical central section of the same. Fig. 3 is a horizontal section taken along the line $\alpha\alpha$ of Fig. 1. Fig. 4 is a view like Fig. 2, on a larger scale of the upper portion of the case, showing the 50 reels in a different position. Fig. 5 is a horizontal section along the line $y-y$ of the same.

In these drawings is shown a case a provided with a sight opening b covered with 55 a sheet of glass c . Along each side of the case at the interior is secured a wall plate

or bracket d each having a channel e and a rim f located respectively at the forward and rear part of the bracket. A carriage consisting of slides g provided with angular projections h are adapted to engage the channels and forward parts of the brackets. These slides are joined together by means of a pair of transverse tubular rods i thereby forming a carriage to move up or down 60 in the channels of the wall plate. At the front portions of the carriage is located a bar j extending centrally from one slide to the other, the object of which will be hereinafter described. The carriage also 65 carries vertically arranged guide plates k secured to the upper and lower portions of the slides.

A pair of reels m are journaled in the sliding plates of the carriage. To each reel 75 is fastened one end of a web of belt n while the other end of each web is secured at o to the respective upper and lower adjacent portions of the case. Both of the reels can be connected together by a belt or as shown 80 in the drawings by gears p so that when the carriage is actuated both reels will rotate to simultaneously wind or unwind the web. The webs are guided to the reels by means of a pair of idler rollers q located at 85 the forward part of the carriage.

It is evident that either one of the webs may be replaced by a web having different pictures thereon without changing the other web. For instance it may be desirable to 90 substitute the upper web with one having depicted thereon a girl's figure having a different form hat or having a different facial expression. It is furthermore evident that stretching of the webs is prevented, as 95 they are rolled directly upon the reels without passing over a plurality of pulleys, and that also excessive wear upon the web is prevented.

Cords or cables r are connected to the 100 upper and lower portions of the carriage. These connections pass over rollers s disposed at the bottom and top of the interior of the case. The end of each cord is secured to a drum t arranged on a driving 105 shaft u at the rear part of the case. This driving shaft can be rotated by belt connection from a pulley v to a motor not shown. The motor can be provided with any well known reversing device whereby 110 the rotation of the shaft u can be reversed.

It will be seen that when the shaft u is

rotated it winds up one of the cords and unwinds the other. Hence actuating the carriage up or down in a rectilinear path and at the same time revolving the reels to wind one of the webs and unwind the other. When the carriage is moving upward the upper reel will be rotated by the pull exerted on the lower web which unwinds the lower reel and by means of the gear connection rotates 10 the upper reel to wind its web. In other words the sliding movement of the carriage either up or down, will by tensioning either of the webs transmit rotary motion to the reels in a direction to unwind one of the 15 webs and wind the other.

The upper and lower web is guided between the vertical plates λ , and the bar to the idler rollers so as to prevent wrinkling or folding of the web. In this construction, 20 the bar β will at all times cover the spaced portions of the idler rollers where the webs branch to the reels; thereby hindering anybody from seeing how the webs are rolled or unrolled from the reels creating the illusion 25 of a dissolving picture or advertisement.

I claim:

1. In a picture exhibitor, the combination with a case provided with a sight opening, of a carriage, a reel mounted upon the 30 carriage, a web connected to the reel and the case, and means for transmitting rectilinear rotary movement to the reel and comprising a driven shaft, a pair of drums on said shaft, and a cord secured to each of said drums 35 and said carriage, one of said cords being unwound when the other is wound upon the drum.

2. In a picture exhibitor, the combination with a case provided with a sight opening, 40 of a carriage, a plurality of reels mounted on the carriage, a web connected to each reel and the case, a driven shaft, a pair of drums on said shaft, and a cord for each of said drums connected to said carriage, said cords 45 being wound in reverse direction to each other upon said drums.

3. In a picture exhibitor the combination with a case provided with a sight opening, of a carriage arranged in the case, a pair of 50 reels mounted on the carriage, a web connected to each reel and the case, means for transmitting rectilinear movement to the carriage for rotating the reels to unwind one of the webs and wind the other.

55 4. In a picture exhibitor the combination with a case provided with a sight opening, of a carriage arranged in the case, a pair of reels mounted on the carriage, a web se-

cured to each reel and adjacent portions of the case, means carried by the carriage for connecting the reels, means for transmitting rectilinear movement to the carriage for rotating the reels to unwind one of the webs and wind the other.

5. In a picture exhibitor the combination with a case provided with a sight opening, 65 of a pair of reels arranged in the case, a web secured to each reel and adjacent portions of the case, a carriage for mounting the reels, gears carried by the carriage for connecting the reels, a bar moving with the carriage for covering the spaced portion of the webs leading to the reels, means for transmitting rectilinear movement to the carriage to unwind one of the webs and wind the other.

75 6. In a picture exhibitor the combination with a case provided with a sight opening, 80 of a pair of reels arranged in the case, a web secured to each reel and adjacent portions of the case, a carriage for mounting the reels, rollers mounted on the carriage for leading the webs to the reels, a bar secured to the carriage for covering the spaced portions of the rollers, means for transmitting 85 rectilinear movement to the carriage to unwind one of the webs and wind the other.

90 7. In a picture exhibitor the combination with a case provided with a sight opening, of channeled wall plates secured in the casting, a carriage coacting with the plates, a pair of reels mounted on the carriage, webs 95 secured to the reels and the case, gears connecting the reels, a bar carried by the carriage for covering portions of the webs, means for transmitting rectilinear movement to the carriage to unwind one of the webs and wind the other.

100 8. In a picture exhibitor the combination with a case provided with a sight opening, 105 of channeled wall plates secured in the casting, a carriage including slides to engage the channels of the plates, a pair of reels mounted on the carriage, webs secured to the reels and the case, gears connecting the reels, a bar carried by the carriage for covering portions of the web, means for transmitting rectilinear movement to the carriage to unwind one of the webs and wind the other.

110 In testimony whereof I have hereunto set my hand in the presence of two subscribing witnesses.

NATHANIEL BRAHAM.
